UNITED STATES PATENT OFFICE.

DANIEL L. HOLDEN, OF NEW YORK, N. Y., ASSIGNOR TO FEDERAL ICE COMPANY, OF NEW YORK, A CORPORATION OF NEW YORK.

LIQUID-STERILIZER.

No. 838,409.

Specification of Letters Patent.

Patented Dec. 11, 1906.

Application filed March 12, 1906. Serial No. 305,527.

To all whom it may concern:

Be it known that I, DANIEL L. HOLDEN, a citizen of the United States, residing at New York, in the county of New York and State 5 of New York, have invented certain new and useful Improvements in Liquid-Sterilizers, of which the following is a specification.

My invention relates to improvements in means for the purification of water by subjecting it to pressure and heat and liberating the same into a vacuum-chamber, by this means killing the bacteria and blowing the water into atoms by the release of its contained pressure, also obviating the necessity 15 of evaporating all of the water, and thereby effecting a great saving of fuel over the common evaporation process.

My mechanism is especially adapted for ice-machines, although it may be utilized for 20 other purposes where water purification is desired.

The mechanism is automatic, cooling-water being first conducted to a condenser, then passing through a heater, and thereafter 25 flows into the condenser intermittently, the inflow being regulated by the vacuum in the condenser, and which automatically controls mechanism for permitting the flow of hot water when the vacuum takes place. 30 The atomized water then flows through a series of perforated plates to scatter it and release the air and then surrounds a system of cooling-pipes, after which it passes to the freezing cylinder-tank. (Not shown.)

35 My mechanism will be explained more in detail in the specification and illustrated in the accompanying drawings, in which—

Figure 1 is a view mostly in central vertical section, some of the details not being 40 in section. Fig. 2 is a plan of the condenser-tube sheets, showing the arrangement of its tubes. Fig. 3 is a section on line X X, Fig. 1, showing a plan of the perforated scattering- 45 plates. Fig. 4 shows the automatic hot-water-releasing mechanism as when closed.

Similar figures of reference indicate similar parts throughout the views.

The condenser is formed by a cylindrical shell 1, to which is secured lower tube-sheet 2 50 by ring 3 and an upper tube-sheet 4, secured by ring 5, and to which a hood 6, forming a

vacuum-chamber 7, is attached. Tubes 8 are secured to sheets 2 4.

The supply of cold water for condensation and to be heated enters by pipe 9 from any 55 suitable source of supply. Pipe 10 is the overflow means from the condenser and delivers the water to the heater 11, formed by a sheet 12, having heads 13 14 secured by rings 15 16, head 13 having a stuffing-box 17 60 and gland 18 and head 14 being similarly provided for by stuffing-box 19, with a gland 20. The stuffing-boxes permit the expansion and contraction of the coil. A pipe 21 enters heater 11 through stuffing-box 17, is then 65 formed into a coil 22, and has its exit through stuffing-box 19 to a steam-trap. (Not shown.) Live steam is supplied to the coil and heats the water in heater 11 to the desired temperature, which thereafter flows through 70 pipe 23 to the expansion and cooling chamber 24 immediately below condenser-tubes 8, which it enters to be atomized, the released vapor rising in tubes 8 and being subjected to the cooling produced on the tubes 75 by the surrounding body of cold water and where it is reconverted to its liquid form, the air passing out through valve 25 and pipe 26, preferably attached to a vacuum-pump.

Expansion and cooling chamber 24 is 80 formed by a sheet 27, the condenser-tube sheet 2, secured by ring 28, and a lower head 29, secured by ring 30. The chamber has a lower stuffing-box 31, with a gland 32, and a side stuffing-box 33, with a gland 34. A cooling-pipe 35 enters through stuffing-box 31, is 85 formed into a coil 36 within the chamber, and passes out through stuffing-box 33, the stuffing-boxes permitting the coil to expand and contract without leakage from the cooling- 90 chamber, the pipe finally passing to a steam-trap. (Not shown.) Above coil 36 a series of perforated plates 37 are supported on a ring 38, secured to sheet 27, with a central rod 39 passing through the plates, and between the plates over the rod are thimbles 40 to separate the plates. The plates thus arranged may be removed in a body for 95 cleansing. The perforations of the plates are shown in Fig. 3. Pipe 41 conveys the 100 cooled water to the freezing cylinder-tank (not shown) and is provided with a check-

valve 42. Chamber 7 has connected thereto a vacuum-pipe 43, leading to casing 44, mounted on a bracket 45, and within the casing is a flexible and yielding diaphragm 46. 5 The diaphragm has a connected rod 47 reaching downward and attached to a lever-pan 48, formed with a bottom part, with upwardly-extending sides and ends, and a rolling weight 49 is placed in the inclosed space 10 formed by the lever-pan. The pan is pivotally fulcrumed on a bracket 50, and toward its outer end a rod 51 is attached, its opposite end engaging a lever 52, operating a valve 53, which opens and closes the pipe 23, 15 a quick opening and closing being insured by the use of the rolling weight 49. Cleaning-hole 54 is provided for heater 11, and 55 for expansion and cooling chamber 24.

The operation of my mechanism is as follows: Heater 11 and its coil 22 having previously received water from condenser 1, it heats it to the desired temperature, when valve 53 being opened by the attendant, as shown in Fig. 1, a volume of hot water enters 25 chamber 24, where it is atomized, and the vapor which is released therefrom arises to tubes 8 of the condenser 1, filling the tubes, chamber 7, pipe 43, and forcing down diaphragm 46, its rod 47, tripping-pan 48, and lifting-rod 51, which closes valve 53, and weight 49 passing inward holds these parts in the closed positions just described, and, as seen in Fig. 4, the cold water surrounding 30 tubes 8 in condenser 1 now cools them and condenses the steam, which as water now descends in the tubes to plates 37 and together with the atomized water is scattered through their perforations, affording opportunity for the release of all air. It then 35 passes to coil 36 to be thoroughly cooled, when it is ready to be drawn off through pipe 41. When condensation takes place, a vacuum is produced in chamber 24, tubes 8, chamber 7, and pipe 43, relieving diaphragm 46 from pressure, when it resumes the position shown in Fig. 1, thereby lifting rod 47, 45 tilting lever-pan 48 downward at its outer end, pushing down rod 50, and operating valve 53 for another inflow of hot water to the expansion and cooling chamber and the condenser, while weight 49 moves outward 50 to hold the valve 53 open, the opening and closing of valve 53 being automatic. It will be evident that any mechanism which is 55 pressure-operated could be substituted for the diaphragm.

I claim—

1. In a water-purifier, a condenser, comprising a cylindrical shell and tubes therein, 60 means to introduce cold water around the tubes, a heater having means for hot-water communication with the interior of the condenser-tubes, means for opening and closing the communication, and means operative by

the action of steam-pressure and its condensation whereby the opening and closing of the communication between the heater and the condenser-tubes is alternately effected. 65

2. In a water-purifier, a condenser, a heating-chamber, an expansion and cooling chamber, a heating-coil in the heating-chamber, a cooling-coil in the cooling-chamber, a water-inlet to the condenser, a communication from the heating-chamber to the condenser and to the expansion and cooling chamber, a valve 70 in the communication and means to open the valve for admission of hot water from the heating to the expansion and cooling chamber and the condenser-tubes, when condensation takes place, and to close the same 75 when steam-pressure exists in the condenser-tubes.

3. In a water-purifier, a condenser having water-surrounded tubes, and means for such water admission, a heater having a coil and means for the passage of water from the condenser to the heater, and hot water from the heater to the condenser within its tubes; automatic means to admit intermittent volumes of hot water from the heater to the condenser; an expansion and cooling chamber in communication with the condenser-tubes, and therein a series of perforated scattering-plates and a cooling-coil for separating and cooling the water of condensation, and releasing the air. 85 90

4. In a water-purifier, a multiple-tube condenser, a coil-heater, an expansion and cooling chamber, with scattering-plates and a cooling-coil, and arranged in the order named, 95 means for their intercommunication, for sterilizing purposes, and an air-valve located on the condenser, available for communication with a vacuum-pipe.

5. In a water-purifier, a condenser, a heater 105 and an expansion and cooling chamber in the order named, means for fluid flowing to the condenser, thence to the heater, for heating to a desired degree; thence to the condenser for condensation; thence to the cooler for 110 cooling; means to automatically control the passing of hot water to the condenser by the alternate action of steam-pressure and a vacuum created by the condensation of the steam released from the hot water. 115

6. In a water-purification system, an expansion and cooling chamber, a cooling-coil therein, a series of scattering-plates, the lower one having side support and centrally supporting the others for easy removal adapted 120 to receive the water of condensation and atomization and retard its progress, to permit the escape of air, and means to removably secure the plates in the cooling-chamber. 125

7. In a water-purifier, a condenser, tubes therein, a vacuum-chamber and an air-valve connected therewith, a heater, a diaphragm

having communication with the condenser-tubes, a connection from the diaphragm to a lever-pan, a fulcrum for the pan, a connection from the pan to a valve located between the condenser and the heater, and a rolling weight located in the pan and adapted to move from end to end of the pan, in manner and form substantially as set forth.

In testimony whereof I have signed my name to this specification in the presence of 10 two subscribing witnesses.
